UNITED STATES PATENT OFFICE.

ALEXANDER S. YOUNG, OF GALESBURG, ILLINOIS.

STREET-SWEEPER.

SPECIFICATION forming part of Letters Patent No. 746,229, dated December 8, 1903.

Application filed February 5, 1902. Serial No. 92,642. (No model.)

To all whom it may concern:

Be it known that I, ALEXANDER S. YOUNG, a citizen of the United States, residing at Galesburg, in the county of Knox and State of Illinois, have invented certain new and useful Improvements in Street-Sweepers, of which the following is a specification.

The present invention relates to that class of sweepers that collect the dirt and deliver it into a cart or wagon as the sweeper proceeds.

It is of course very desirable to confine as much as possible the dirt and dust thrown up by the broom, and thus avoid littering the sidewalk and adjoining property, and this is particularly so when the sweeper is used during the day, else pedestrians would be annoyed and discomfited by clouds of dust; and one object of the present invention is to provide improved means for accomplishing this very desirable result. To this end I inclose the broom in a hood which is made as tight as circumstances will permit, and I connect this hood with a closed wagon by means of a closed chute, in which the upper or ascending lap of the endless conveyer travels. It is also desirable to revolve the broom with certainty, and thus prevent it from either rolling or dragging upon the ground, else it will not give the dirt the forward impetus necessary to throw it onto the conveyer. Heretofore in sweepers of the class to which the present invention belongs the broom has derived its motion from the wheels of its supporting-carriage; but the weight of this portion of the machine is not sufficient to produce the necessary traction under all conditions.

Another object of the invention is to provide improved means for driving the broom when the latter is supported by a carriage which is independent of the collecting-wagon, to the end that it shall revolve constantly at a speed proportional to that of the sweeper, and to this end I drive it from the rear wheel of the collecting-wagon by some suitable mechanism, such as sprocket-wheels and chain. It is also desirable that little or none of the work of dragging the broom-carriage and its accessories be put upon the chute, else it would be necessary to make the chute objectionably heavy in order to give it the necessary strength; and another object of the

invention is to provide means independent of the chute for dragging the broom-carriage and its accessories. To this end I connect some part of the broom-carriage with the wagon by means of a draw bar or bars or other suitable device.

Another object of the invention is to provide improved means for adjusting the broom vertically.

Another object of the invention is to provide improved means for adjusting the rear roller, over which the endless carrier runs, in order that it may be placed and maintained in proper relation to the broom.

Other minor objects of the invention will appear hereinafter.

The invention consists in the features of novelty herein described, and in order that it may be fully understood I will describe it with reference to the accompanying drawings, which are made a part of this specification, and in which—

Figure 1 is a side elevation of a street-sweeper embodying the invention with portions broken away. Fig. 2 is a longitudinal section thereof. Figs. 3 and 4 are transverse sections of portions thereof on the lines 3 3 and 4 4, respectively, Fig. 2.

Only a portion of the receiving wagon or cart is shown in the drawings. It comprises a body portion 1, made of wood, and a housing or cover 2, resting removably upon the body portion 1 and forming therewith a tight joint at all points where this is practicable. In the floor of the wagon is a trap-door 3, held up by any suitable fastening device and adapted to be let down for emptying the wagon of its contents. In the top of the cap or cover 2 is an opening provided with a cover 4, which cover may be opened to uncover the opening when it is desired to use the wagon without the means hereinafter described for sweeping up the dirt and automatically delivering it into the wagon. At the rear end of the cap or cover 2 is a short hollow socket 5, adapted to telescope with the upper end of a chute 6, which inclines downward, its lower end being connected with a forwardly-projecting portion 7 of a drum 8. The chute 6 is closed on all sides from its top to the point of attachment to the hollow projection 7 and has in its top an opening closed by a door 60. The

ends of the hood 8 are closed by heads 9, which are slotted at 91 for the passage of a shaft 10, carrying the broom 11, said shaft being journaled in boxes 12, supported by hangers 13, which pass through guide-brackets 13^a, secured to the heads of the hood. In Fig. 4 the hangers are shown partly in section and partly in elevation. The hangers 13 pass upward through the shaft or axle 15 of the ground-wheels 16, by which all of the rear portion of the sweeper is carried. The portions of the hangers which pass through the shaft 15 are threaded, and nuts 14 are turned onto them and bear upon the top side 15 of the shaft, so that by turning the nuts one way or the other the broom-shaft 10 may be raised or lowered, as desired. The broom derives its motion from one of the rear wheels 16 of the cart or wagon.

20 17 is a master gear-wheel secured to the ground-wheel 16 by means of brackets, clips, or other suitable devices 18. This master-gear-wheel meshes with a pinion 19, secured to a shaft 20, journaled in suitable bearings 25 21, supported by the wagon. 22 is a sprocket-wheel secured to the shaft 20, and 23 is a sprocket-chain passing around the sprocket-wheel 22 and also around a sprocket-wheel 24, secured to the broom-shaft 10. With this arrangement the rotation of the ground-wheel 16 will be transmitted to the gear 19, its direction being reversed in the transmission, and the rotation of the gear 19 will be transmitted to the broom-shaft 10 without reversal. The broom is thereby revolved in a direction the reverse of that of the ground-wheels, and its lower side sweeps forward, throwing the dirt and dust ahead of it. The dirt and dust thus thrown forward are caught 30 by blades 25, which are secured to an endless belt 26, the blades and belt forming an endless carrier by which the dirt is carried upward and dumped into the wagon. At this upper or forward end the endless carrier passes around a roller 27, fixed to a shaft 28, carrying a pinion 29, which meshes with the gear 19, said shaft being journaled in bearings 30, supported by brackets 31, secured to the sides of the wagon-body. At its 35 lower or rear end the endless carrier passes around a roller 32, carried by a shaft 33, journaled in boxes 34, the boxes being carried by hangers 35, which are adjustable vertically. These hangers pass through brackets 36, secured to the sides of the chute, and pass also through a stout cross-bar 37, secured to the top of the chute and crossing it from side to side. The portions of the hangers 35 which pass through the cross-bar 37 are threaded, 40 and onto these threaded portions are turned nuts 38, bearing upon the top side of the cross-bar, so that by turning the nuts in one direction or the other the hangers 35 may be moved upward or downward, and thus raise 45 or lower the roller 32, by which the rear end of the endless conveyer is carried. The upper run of the endless conveyer travels within

the chute, the bottom of the chute being provided at its upper end with a curved sill 39, over which the conveyer passes to the roller 70 27. The roller 32 is so placed that the blades 25 of the endless conveyer will just clear the ascending side of the brush, and their curved form enables them to retain the dirt better than could be done with straight blades. 75 They are located at sufficiently close intervals to insure that the space between the depending apron-like sides 40 of the chute will always be closed by one of them, thus preventing any dirt or dust thrown forward from escaping 80 under the conveyer. As will be seen, these aprons 40 extend forward past the roller 32.

For the purpose of dragging the broom-carriage and relieving the chute of this duty draw bars or rods 41 are used. These draw-bars are preferably connected at their forward ends to the axle 42 of the rear ground-wheels 16 of the wagon and at their rear ends to the brackets 13^a, so that there is a direct pull from the rear axle 42 to a point on the 90 broom-carriage between its axle and the shaft of the broom. These draw-bars are preferably rigid, so that they will not only draw the rear part of the machine forward, but will also force it backward, and thus prevent 95 injury to the chute in the event of a backward movement of the wagon.

Having thus described my invention, the following is what I claim as new therein and desire to secure by Letters Patent:

1. In a street-sweeper the combination of a wagon, a broom-carriage located behind the wagon and having a single pair of ground-wheels and an axle carried by them, means for connecting the wagon and broom-carriage, 100 a shaft located beneath the axle, means supported by the axle and in turn supporting said shaft, a broom carried by said shaft, means actuated by a ground-wheel of the wagon for revolving said shaft, an endless 105 conveyer, and means actuated by a ground-wheel of the wagon for driving said carrier, substantially as described.

2. In a street-sweeper, the combination of a closed wagon, a chute closed on all sides, extending downward and rearward therefrom, 110 a broom-carriage independent of the wagon, draw-bars connecting the broom-carriage and wagon, a hood carried by the broom-carriage, a broom within the hood, a shaft carried by 115 the broom-carriage and in turn carrying the broom, means actuated by a rear wheel of the wagon for revolving the shaft, an endless conveyer, means actuated by a rear wheel of 120 the wagon for driving said conveyer and aprons depending from the sides of the chute and extending from the drum forward beyond the rear end of the conveyer, the conveyer being provided with blades adapted to 125 close the space between said aprons, substantially as described.

3. In a street-sweeper, the combination of a wagon, a broom-carriage located behind the wagon and having a single pair of ground-

wheels and an axle carried by them, a shaft located beneath the axle, means supported by the axle and in turn supporting said shaft, a broom carried by said shaft, rigid draw-bars having their forward ends connected to the wagon and their rear ends connected to the broom-carriage at points between the axle and the broom-shaft, means actuated by a ground-wheel of the wagon for revolving the broom-shaft, an endless conveyer having its rear end supported by the broom-carriage and its forward end supported by the wagon, and means actuated by a ground-wheel of the wagon for driving the conveyer, substantially as described.

4. In a street-sweeper, the combination of a wagon, a broom-carriage located behind the wagon and having a single pair of ground-wheels and an axle carried by them, means for connecting the wagon and broom-carriage, a shaft located beneath the axle, means supported by the axle and in turn supporting said shaft, a broom carried by said shaft, a hood supported by the axle and covering the broom, a chute having its rear end supported by the hood and its forward end supported by the wagon, means actuated by a ground-wheel of the wagon for revolving the broom-shaft, an endless conveyer having its rear end supported by the broom-carriage and its forward end supported by the wagon and means actuated by a ground-wheel of the wagon for driving the conveyer, substantially as described.

35 5. In a street-sweeper, the combination of a wagon, a chute extending downward and rearward therefrom, a broom-carriage located behind the wagon and having a single pair of ground-wheels and an axle carried by them, means for connecting the wagon and broom-carriage, a shaft located beneath the axle, means supported by the axle and in turn supporting said shaft, a broom carried by said shaft, a sprocket-wheel on said shaft, a sprocket-chain embracing said sprocket-wheel, a second sprocket-wheel embraced by said chain, a shaft carrying the second sprocket-wheel and supported by the wagon and means for transmitting movement from the ground-wheel of the wagon to the shaft last aforesaid, substantially as described.

6. In a street-sweeper, the combination of a wagon, a chute extending downward and rearward therefrom, a broom-carriage located behind the wagon and having a single pair of ground-wheels and an axle carried by them, means for connecting the wagon and broom-carriage, a shaft located beneath the axle, means supported by the axle and in turn supporting said shaft, a broom carried by said shaft, a sprocket-chain embracing the sprocket-wheel, a second sprocket-wheel embraced by the chain, a shaft carrying said second sprocket-wheel and supported by the wagon, means for transmitting movement from a ground-wheel to the shaft last aforesaid, an

endless conveyer, rollers carried by the broom-carriage and wagon respectively and embraced by said conveyer and means actuated by a ground-wheel of the wagon for driving the roller carried by the wagon, substantially as described.

7. In a street-sweeper, the combination of a wagon, a chute extending downward and rearward therefrom, a broom-carriage located behind the wagon and having a single pair of ground-wheels and an axle carried by them, means for connecting the wagon and broom-carriage, a shaft located beneath the axle, means supported by the axle and in turn supporting said shaft, a broom carried by said shaft, a sprocket-wheel carried by said shaft, a sprocket-chain embracing said wheel, a second sprocket-wheel embraced by the chain, a shaft carrying said second sprocket-wheel and supported by the wagon, a gear carried by said shaft, a master gear-wheel carried by a ground-wheel of the wagon and meshing with the gear-wheel first aforesaid, a pinion meshing with said gear-wheel first aforesaid, a shaft supported by the wagon and carrying said second pinion, a roller carried by said shaft, an endless conveyer passing around said roller, a second roller around which said endless conveyer passes, a shaft carrying said second roller and bearings supported by the broom-carriage and in turn supporting the shaft last aforesaid, substantially as described.

8. In a street-sweeper, the combination of a wagon, a chute extending rearward and downward therefrom, a broom-carriage, independent of the wagon, having a pair of ground-wheels and an axle connecting them, a hood supported directly by said axle, a broom within the hood, a shaft carrying the broom, boxes in which the shaft is journaled, hangers supporting said boxes and in turn supported directly by said axle, means for adjusting the hangers, and means actuated by a ground-wheel of the wagon for revolving the broom, substantially as described.

9. In a street-sweeper, the combination of a wagon, a chute extending downward and rearward therefrom, a broom-carriage independent of the wagon, having a pair of ground-wheels and an axle connecting them, a hood carried directly by the axle, a broom within the hood, a shaft carrying the broom, boxes in which the shaft is journaled, hangers carrying the boxes and extending upward therefrom, the upper portions of said hangers being threaded and the axle being provided with openings through which the threaded portions of the hangers pass, nuts turned onto said threaded portions and bearing upon the axle, and means actuated by a ground-wheel of the wagon for revolving the broom, substantially as described.
